J. SMALLMAN.

AIR PUMP.

No Printed Specification Available

Patented Aug. 29, 1815.

Plan of the top and bottom

o Opening to get at the valves.

James Smallman

Aug. 29, 1815

Letters Patent

The Schedule referred to in these Letters Patent, will make part of the same, containing a description in the words of the said James Smallman himself of his double air and water pump.

The principles of this pump are as follows, viz. It works a double stroke of water in one working barrel by forcing the length of its stroke of water out below, and the same above, by the use of two or more valves in the rising main, the one at the bottom over the other at the top, and two or more valves, according to the size of the pump, for the suction or supplying pipe. It is so constructed as to work in a perpendicular, or any angle down to 45 degrees, with any number or shape of valves in each opening according to the size of the pump, as the more valves the more easy their motion. It can also be worked with one or more horizontal valves of a conical shape.

The double Pump works very well either with or without an air vessel; as I have them in actual operation from 3 inches to 20 inches, and from 30 to 98 feet in depth without any aid derived from an air vessel.
